UNITED STATES PATENT OFFICE.

GUSTAF DALÉN, OF LIDINGÖN, STOCKHOLM, SWEDEN.

APPARATUS FOR AUTOMATICALLY EXCHANGING INCANDESCENT BODIES IN AN INCANDESCENT-GAS-LIGHT ARRANGEMENT.

1,251,343.

Specification of Letters Patent. Patented Dec. 25, 1917.

Application filed November 2, 1917. Serial No. 199,913.

To all whom it may concern:

Be it known that I, GUSTAF DALÉN, engineer, residing at Skärsätra, Lidingön, Stockholm, Sweden, have invented certain new and useful Improvements in Apparatus for Automatically Exchanging Incandescent Bodies in an Incandescent-Gas-Light Arrangement, of which the following is a specification.

10 This invention has reference to apparatus for automatically exchanging incandescent bodies for gas flame burners in an incandescent gas light arrangement of the kind in which an additional or reserve incandescent body, by the action of the burner flame upon a releasing device is automatically rendered active when a previously active incandescent body breaks. For this purpose it has been proposed to employ a pin or the like of a material which is burnt, melted or weakened by the influence of heat, and which coöperates with a stop that keeps the additional incandescent body in its place, but which is destroyed when played upon by the burner 15 flame so that the stop is released and allows movement of the additional or reserve incandescent body to the plane of the incandescent body which previously was active.

The invention has for object to provide 20 simple and efficient apparatus of the said kind.

A construction of apparatus embodying the invention is shown on the accompanying drawing by way of example, Figure 1 showing the apparatus in vertical section, and Fig. 2 showing it in transverse section, certain parts being shown in plan.

25 A number of frames 1, 2, 3, 4, each carrying an incandescent body 5, are provided in a cylindrical casing 6 located below the burner 7. The frames 1, 2, 3, 4, comprise bars, jointed at their lower ends to the casing 6 by means of parallel links 8 and 9, whereby each frame receives a parallel movement in 30 a radial direction simultaneously as it is raised or lowered.

One of the links 8 or 9 of each frame carries a roller 10 that rests on a track 11, part 35 of which forms a cam 12. The track 11 is carried by a support 13, which can rotate on a central pivot 14 at the lower part of the casing 6. The support 13 together with the track 11 may be rotated by means of any suitable device for example by means of a

spring 15 and transmission gear 16 engaging 55 a toothed ring 17 on the support 13.

The upper member 18 of each of the frames 1, 2, 3, 4, is provided with a holder 19 for the corresponding incandescent body, said holder 19 on the inside fitting the lower 60 part 20 of the burner 7. The member 18 is at its lower part formed as a sleeve 21, movable on the corresponding frame member 1, 2, 3, or 4. A spring 22 tends to draw the frame member 18 down, but said member 65 may be kept in its raised position by placing a pin 23 of a material which is destroyed by the action of a flame, say a combustible material, between a forked arm 24, projecting from the frame member 18, and the upper end of the corresponding frame member 1, 2, 3, or 4.

When the device is working one of the frames, the frame 1 for example, takes the position shown on Fig. 1 of the drawing 75 with its roller 10 resting on the track 11 near the highest point of the cam part 12 thereof. In this position the holder 19 of the corresponding incandescent body surrounds the lower part 20 of the burner 7. 80 The frame 1 is thereby fixed in position and prevents the track 11 from rotation although the driving device of the track, the spring 15 in the example shown, constantly tends to rotate the track farther and to lift the 85 frame higher but is prevented from doing so as the holder 19 of the incandescent body abuts against the burner 7 which thereby acts as a stop. When a flame is burning in the burner 7 the incandescent body 5 of the 90 frame 1 will glow, if however said incandescent body breaks, the flame in the burner 7 will impinge upon the pin 23 so that it will be consumed or destroyed in any other manner. The spring 22 can then draw the 95 frame member 18 down so that the holder 19 of the incandescent body will be released from the burner member 20, and will move down into the dotted line position shown in Fig. 1.

The track 11 can then continue its movement whereby the highest point of the cam part 12 passes beneath the roller 10 and lifts the frame farther upward, whereafter the frame 1 sinks and resumes its original position on the horizontal part of the track 11. Simultaneously the frame 2, the roller 10 of which is situated at the beginning of the

cam 12, is raised upward by the cam, whereby the same simultaneously moves radially toward the center of the casing 6, so that at last it will take the same position as the frame 1 previously had right under the burner 7, and surrounding the burner part 20 with the holder 19 of the incandescent body. The frame 2 is then prevented by said burner member from being further raised so that the further movement of the track 11 is prevented before the highest point of the cam has passed beneath the roller 10.

When, as in the construction shown, four frames, each carrying an incandescent body, are employed, the cam part 12 extends over a fourth of the periphery of the track 11, whereas the remaining part of the track 11 is horizontal. An incandescent body will consequently enter in position beneath the burner at each quarter of a revolution of the track 11. When more or less incandescent bodies are employed, the cam part 12 will be correspondingly arranged.

Having now fully described my invention what I claim is:

1. In an apparatus for exchanging incandescent bodies, a burner, an incandescent body, an additional incandescent body, means for automatically bringing said body into active position by the influence of the burner flame, a releasing device for said additional body, a frame for said body, comprising a link and lever system, a driving device, actuating said system, and means for controlling the action of said driving system.

2. In an apparatus for exchanging incandescent bodies, a burner, an incandescent body, an additional incandescent body, means for automatically bringing said body into active position by the influence of the burner flame, a releasing device for said additional body, a holder for said body, a driving device actuating said holder, comprising a cam for moving the additional incandescent body in and out of engagement with the burner.

3. In an apparatus for exchanging incandescent bodies, a burner, an incandescent body, an additional incandescent body, means for automatically bringing said body into active position by the influence of the burner flame, a releasing device for the additional body, a frame for said body, comprising a bar, articulated by parallel links to a casing, and a rotating cam, actuating the additional incandescent body for moving the same in and out of engagement with the burner.

4. In an apparatus for exchanging incandescent bodies, a burner, an incandescent body, a frame for said body, and a holder for the body, movable on the frame, and kept in engagement with the burner by means of a pin, adapted to be destroyed by the flame of the burner.

5. In an apparatus for exchanging incandescent bodies, a burner, an incandescent body, a holder for said body, fixed to a movable member, a spring actuating said member, and a pin, tending to keep the holder in engagement with the burner against the action of said spring and adapted to be destroyed by the burner flame.

6. In an apparatus for exchanging incandescent bodies, a burner, an incandescent body, a plurality of frames, carrying additional incandescent bodies and their holders, a casing, to which said frames are articulated, and a rotating track, comprising a cam in engagement with said frames.

In testimony whereof I have signed my name to this specification in the presence of two subscribing witnesses.

GUSTAF DALÉN.
